UNITED STATES PATENT OFFICE.

JOHN HENRY KELLERHALS, OF BENTON CITY, MISSOURI.

HEDGE-TRIMMING ATTACHMENT FOR HARVESTING-MACHINES.

SPECIFICATION forming part of Letters Patent No. 349,595, dated September 21, 1886.

Application filed January 4, 1886. Serial No. 187,542. (No model.)

To all whom it may concern:

Be it known that I, JOHN HENRY KELLERHALS, a citizen of the United States, and a resident of Benton City, in the county of Audrain 5 and State of Missouri, have invented certain new and useful Improvements in Hedge-Trimming Attachments to Harvesting-Machines; and I do hereby declare that the following is a full, clear, and exact description of the invention, 10 which will enable others skilled in the art to which it appertains to make and use the same, reference being had to the accompanying drawings, which form a part of this specification, and in which—

15 Figure 1 is a perspective view of as much of a harvesting-machine as will illustrate the construction and application of my attachment for trimming the tops of hedges. Fig. 2 is a similar view of the attachment detached from 20 the machine. Fig. 3 is a perspective of a portion of a harvesting-machine, showing an attachment for trimming the sides of hedges; and Fig. 4 is a similar view of the latter attachment detached from the machine.

25 Similar letters of reference indicate corresponding parts in all the figures.

My invention has relation to hedge-trimming attachments for harvesting-machines, reapers, or mowers; and it consists in the improved construction and combination of parts constituting the same, as will be hereinafter fully set forth.

In the accompanying drawings, the letter A indicates a portion of the platform of the harvesting-machine. B is the drive-wheel. C is the crank-shaft, and D is the disk having the crank-pin or wrist-pin E at its end.

F is the finger-bar having the shoe G at its inner end.

40 H is the cutter-bar having the coupling-lips I at its inner end.

J is the coupling-bar, to which the lifting-chain K is secured, and L is the thrust-bar, which is normally attached to the inner end of 45 the finger-bar and to the forward portion of the machine-frame.

M is an upright bar having a transverse perforation, N, at its lower end, through which the rear end of the thrust-bar is inserted, said 50 end projecting beyond the upright bar, and being rounded to receive the outer end of the

coupling-bar. The upper portion of the upright bar is braced and retained in its upright position by means of a rod, O, secured to the machine-frame and to the upright. At the 55 middle of the inner side of the upright two lips, P P, formed upon a plate secured to the face of the upright, and a lever, Q, is pivoted between these lips, rocking in a plane transverse to the draft of the machine. The 60 upper end of the upright is provided with two upwardly-projecting bolts, Q' Q', by means of which the finger-bar is secured to the top of the upright, and the finger-bar is furthermore braced by means of a brace-rod, S, having its 65 upper end secured to the finger-bar, while the lower end of the brace is formed with a longitudinal slot, T, and with a corrugated or serrated face, U, which bears against a correspondingly corrugated or serrated face, V, upon the 70 outer side of the upright, which face is provided with a bolt, W, which passes through the slot and is provided with a nut, X, by means of which the slotted end may be adjusted, thus adjusting the level of the finger-bar. 75 The upper end of the lever is provided with a short pitman, Y, pivoted to the lever and pivoted to the coupling-lips I of the cutter-bar, and the lower end of the lever has pivoted there-to a pitman, Z, which is pivoted at its inner end 80 to the wrist-pin of the revolving disk, so that the lever will be rocked when the disk is revolved and the cutter-bar will be reciprocated at the upper end of the upright, which, by means of the coupling-bar, lifting-chain, and 85 the thrust-bar, may be raised or lowered to the desired height in the same manner as the finger-bar is raised or lowered when operating the harvester for its original purpose.

In Figs. 3 and 4 is shown an attachment for 90 trimming the sides of a hedge, in which the upright is dispensed with and a block, A', secured movably with its inner end to the rear corner of the machine-frame. The coupling-bar is secured to the under side of the outer 95 end of the bar, and the bar or block may in this manner have its outer end raised or lowered at will by the lifting-chain. A flat bar, B', has a clip, C', at its inner end, which clasps the coupling-bar immediately outside 100 of the place at which it is fastened to the bar, and the outer end of the coupling-bar is se-

cured by means of a bolt and nut, E', to the middle of the flat bar, the outer end of which is formed with a perforation or eye, F'. The forward end of the thrust-bar is secured to the forward end of the machine-frame and has its rear end passed through the shoe of the finger-bar in the usual manner and through the eye at the outer end of the flat bar, and the finger-bar is held in a vertical position by means of a brace-rod, G', secured to the frame and to the outer portion of the finger-bar. A bracket, H', is secured to the under side of the bar or block, and has two perforated lips, I' I', between which the hollow portion J' of a rocking connecting-rod is pivoted, and the outer end of this pitman or lever is pivotally connected to the coupling-lips of the inner end of the cutter-bar. The inner end of the lever is hollow and forms a socket, K', within which the end, L', of a bar, M', slides, the inner end of which bar is pivotally connected to the wrist-pin of the revolving disk. It will be seen that as the disk is revolved the sliding pitman will rock the lever, which will reciprocate the cutter-bar vertically, and the flat bar secured to the coupling-bar will bring the finger-bar sufficiently to the side to allow the horses in front of the machine to pass freely along the hedge and to bring the finger-bar as close to the hedge as may be desired for trimming it.

The attachment may have small changes made for the purpose of adapting it to different harvesting-machines, but the principle will remain the same, and all the parts of the harvester are used together with the attachment, which may be easily secured to the machine, as well as easily removed from the same, when the machine will be in order for using it in its proper capacity as a reaping machine or mower.

Having thus described my invention, I claim and desire to secure by Letters Patent of the United States—

45 1. In a hedge-trimming attachment for harvesting-machines, the combination of an upright secured to the machine, and having a pair of lips upon the middle of its inner side,

a finger-bar secured to the upper end of the upright and having the cutter-bar sliding in it, a lever pivoted between the lips upon the upright, a pitman pivoted to the upper end of the lever and to the cutter-bar, and a pitman pivoted to the lower end of the lever and to the wrist-pin of the driving-disk, as and for the purpose shown and set forth.

2. In a hedge-trimming attachment for harvesting-machines, the combination of an upright having a transverse perforation at its lower end, the coupling-bar of the machine inserted through the perforation, the chain-bar of the machine secured at its outer end to the rear end of the thrust-bar, a lever pivoted between lips at the middle of the inner face of the upright, a finger-bar having a cutter-bar sliding in it and having a shoe at its inner end, bolts at the upper end of the upright, a brace-rod secured to the finger-bar and secured adjustably with its lower end to the outer side of the upright, a brace-rod secured to the machine and to the upright, a pitman secured to the upper end of the lever and to the inner end of the cutter-bar, and a pitman pivoted to the lower end of the lever and to the wrist-pin of the drive-disk, as and for the purpose shown and set forth.

3. In a hedge-trimming attachment for harvesting-machines, the combination of an upright secured to the machine-frame at its lower end, a finger-bar secured at its inner end to the upper end of the upright, projecting laterally, a brace-rod secured at its upper end to the finger-bar and having its lower end slotted and provided with a serrated face, and a serrated plate upon the upright having an outwardly-projecting bolt, as and for the purpose shown and set forth.

In testimony that I claim the foregoing as my own I have hereunto affixed my signature in presence of two witnesses.

JOHN HENRY KELLERHALS.
